(57) CLAIM

The ornamental design for a golf club stand, as shown and described.

DESCRIPTION

FIG. 1 is a left-side perspective view of a gold club stand in accordance with the present invention;

FIG. 2 is a rear elevation of the golf club stand of FIG. 1; FIG. 3 is a front elevation of the golf club stand of FIG. 1; FIG. 4 is a right elevation of the golf club stand of FIG. 1; FIG. 5 is a left elevation of the golf club stand of FIG. 1; FIG. 6 is a top plan view of the golf club stand of FIG. 1; and,

FIG. 7 is a bottom plan view of the golf club stand of FIG. 1.

The broken lines in FIG. 1 are for illustrative purposes only and form no part of the claimed design. The article is not limited to the scale shown herein.

FIGS. 2-5 have been shown broken away for ease and clarity of illustration.
